ATTORNEY

UNITED STATES PATENT OFFICE.

WILLIAM EVANS, OF OAK LANE, PENNSYLVANIA, ASSIGNOR TO WILLIAM EVANS,
JOHN H. EVANS, AND ROBERT EVANS, A FIRM TRADING AS JOHN EVANS' SONS, OF
PHILADELPHIA, PENNSYLVANIA.

SHOCK-ABSORBER.

1,128,964.

Specification of Letters Patent. Patented Feb. 16, 1915.

Application filed June 30, 1914. Serial No. 848,115.

To all whom it may concern:

Be it known that I, WILLIAM EVANS, a citizen of the United States, residing at Oak Lane, in the county of Montgomery and 5 State of Pennsylvania, have invented certain new and useful Improvements in Shock-Absorbers, of which the following is a specification.

My invention relates to certain improvements in constructive arrangement of a shock-absorber for application to motor-cars of the Ford and other types and with means connected therewith for adjusting the shock absorbing spring to readily adapt the said 10 absorber to varying conditions without disassembling the parts thereof; and in such connection my present invention relates more particularly to the constructive arrangement of the coiled spring within a concealed 15 grease contained housing and operative independently of said housing by means of a hanger connected with a member of the running gear. The housing is suspended and supported in vertical position by means of a 20 removable base journaled to a bolt carrying links coupled to a second-bolt with which one of the terminal members of the motor 25 spring is attached, whereby shocks and jars occasioned either by the direct action of the 30 wheels or otherwise can be efficiently equalized and relieved.

The nature, scope and characteristic features of the shock absorber of my said invention will be more fully understood from the 35 following description taken in connection with the accompanying drawings forming part hereof, in which—

Figure 1, is a rear elevational view of so much of a motor-car of the Ford type as 40 illustrated, as will serve to disclose in application thereto a shock-absorber, embodying the essential features of my said invention. Fig. 2, is a vertical central sectional view, partly in elevation, of the absorber, showing 45 the detail arrangement thereof, detached from the motor vehicle or car, and also showing fully the mode of adjusting quickly and effectively the housed shock-absorbing coiled-spring and the means arranged to 50 be connected with respectively the running gear and motor-spring for actuating and controlling the action of both the said coiled spring and housing concealing the same, movable independent of each other; and

Fig. 3, is an elevational view, partially in broken section of more particularly the movable link connection supporting the housing for said shock-absorbing spring and connection with a terminal of the car or vehicle cross spring.

Referring to the drawings *a*, is the motor-car having as shown, a leaf cross-spring *a*¹, wheels *a*² and an axle *a*³, and which wheels are provided with brake control hubs *a*⁴, of any well known constructive arrangement, 65 the form shown being of that of the Ford type.

b, is the shock-absorber of my present invention, consisting of a cylindrical housing *b*¹, having a removable recessed and perforated cap *b*², through which depends a threaded bolt *b*³, carrying a tightening nut *b*⁴, thereon, adapted to be brought into a position so as to bear against the recessed part *b*⁵, of the said cap. The bottom of the tubular housing *b*¹, is provided with a removable perforated base *b*⁶, having two depending perforated bars or projections *b*⁷ and *b*⁸, as illustrated in Fig. 3, mounted on a cross-bolt *b*⁹. This bolt carries loose thereon links *b*¹⁰ and *b*¹¹, and which links are similarly mounted on a second cross-bolt *b*¹², on which is also mounted one of the terminals of the leaf car-spring *a*¹ of the vehicle, as clearly shown in Fig. 1. In the housing *b*, is mounted a coiled spring *c*, abutting at its upper extremity against a recessed or offset gasket or disk *b*¹³, and on the opposite side the said threaded tightening bolt *b*³, engages as clearly shown in Fig. 2, to compress the said 80 coiled-spring *c*, or to lessen the extent of compression thereof *ad libitum* within the housing and without affecting said housing. At the opposite extremity, the said spring occupies a position in engagement with a seat *e*, formed into a hollow tube *e*¹ and extending for some distance vertically into said housing surrounded by said spring beyond the base *b*⁶ of said housing, and formed into a curved depending hanger or fixture 100 *b*¹⁴ having an eye to positively engage as shown in Fig. 1, one of the rear wheel hub brake casings *a*⁴, by means of a bolt *b*¹⁵. It will be understood that the said coil spring is mounted in grease within the said housing. The arrangement of the absorber is such 105 that any shocks or jars incident to the action of the wheels will tend to cause a cer-

tain limited compression of the coiled spring within the housing b^1 , independently of the movement of the housing through the linked connection of the same with the car spring and thereby to efficiently compensate for such jars and shocks uniformly and thus assuring greater ease of action of the car, without regard to what the character or condition of the roads may be, over which it is traveling.

Having thus described the nature and objects of my invention, what I claim as new and desire to secure by Letters Patent is:—

In a shock-absorber, a single cylinder, a guide mounted in the lower end of the cylinder and having a depending extension with

means for engaging running gear therewith, a coiled spring supported by said guide, a removable base secured to said cylinder having as part downwardly extending and diametrically arranged lugs and pivotal links in connection therewith and adapted to engage a cross-axle spring, substantially as and for the purposes described.

In witness whereof, I have hereunto set my signature in the presence of the two subscribing witnesses.

WILLIAM EVANS.

Witnesses:
